BLOWER

Frederick W. Parks and Lee L. Smalley, South Bend, Ind., assignors to Bendix-Cowdrey Brake Tester, Inc., South Bend, Ind., a corporation of Delaware

Application November 16, 1936, Serial No. 401,592

11 Claims. (CL 210—50)

This invention relates to blowers and is illustrated as embodied in a novel compact device for providing a blast of heated air such as may be utilized in drying the tires of an automobile mounted on a brake testing machine so that the tires will not slip on the dry rolls of the testing machine. Various features of novelty relate to the arrangement of the heating element to act on the air, to the construction of the tool in two parts including a head and a handle having an advantageous relative arrangement, to the arrangement of the air passages so that the exterior of the tool will be kept cool even when the air is highly heated, to a novel control element which is preferably arranged to control both the air and the electric current, and to various other novel and desirable features of construction which will be apparent from the following description of the illustrative embodiment shown in the accompanying drawing, in which:

The figure is a section longitudinally through the tool showing the parts in section.

While various features of the invention can be utilized in air blowers and the like for other purposes, we have particularly in mind a tool suitable for supplying a blast of hot air which can be directed on the tires of an automobile to dry them so that they will not slip upon the dry rolls of a brake testing machine. Having this object in mind, the device includes generally a cup-shaped head formed with an inner wall 10 and an outer wall 12 defining a cup-shaped chamber between them through which the air passes so that the exterior of the wall 12 is always cool, even though the air blast is highly heated. The inner wall 10 is spun over and fitted into the mouth of the outer wall 12 and there secured by means such as set screws 14 which also hold a cover plate 16.

The central part of the cover plate is drawn downwardly to form a cup-shaped deflector 18 which projects into the interior of the inner wall 10 to define an annular chamber 20 through which the air is directed by the deflector 18 as it enters through an opening 22 in the base of the inner wall 10. The cover plate 16 is formed with suitable openings 24, preferably arranged in an annular series opposite the annular chamber 20 through which the air is directed outwardly in an annular current or blast.

The air is heated as it passes through the annular chamber 20 by a suitable electric resistance coil or unit 26 arranged therein and one end of which is secured to a bracket 28 car-

nied by an insulating washer 30 passing through the wall 10 and formed with a central passage for a conducting screw 32 connecting an insulated conductor 34 in the space between the walls 10 and 12 with one end of the resistance unit 26. 60 The other end of the resistance unit 26 is connected to a bracket 36 electrically connected through screw-threaded members 38 passing through insulating washers 40 and 42 with an insulated flexible conductor 44 outside of the 65 wall 12. The conductor 34 is also electrically connected to a member 46 passing through an insulated washer 48 in the base of the outer wall 12 and which is connected with an insulated flexible conductor 50. 70

A separately formed hollow handle 52, within which the conductors 44 and 50 are arranged, is secured to the base of the above-described double-walled head by bolts or other fastenings. The conductors 44 and 50 are connected, or one 75 of them is connected, to a switch 54 mounted inside of the handle and which may be of any desired form and which in turn is connected to a lead 58 extending through an insulated, washer 56 in the lower end of the handle and 80 which forms an extension wire adapted to be plugged into a base plug or the like. The operating member 60 of the switch 54 is provided with a spring such as a leaf spring 62 rigidly secured thereto and projecting outwardly 85 through the side of the handle. Pressure on the leaf spring 62 rocks the lever 60 to close the circuit through the resistance unit 26 and when the pressure on the spring 62 is released, the circuit is interrupted. 90

The handle also contains a pipe or outlet 64 projecting outwardly through the lower end of the handle and threaded to be attached to a flexible hose connection in the form found leading from the tanks in filling stations and service stations and which supplies air at approximately 150 pounds pressure for inflating tires and the like. The upper end of the conduit 64 is threaded into a plug 66 mounted inside of the handle and in communication with a passage 68 100 which communicates with a valve chamber 70 within which is arranged a poppet valve 72 together with a valve spring 74 urging the valve against its seat. The part of the valve chamber 70 below the poppet valve 72 is connected 105 by a passage 76 with the annular space between the inner and outer walls 10 and 12 of the cup-shaped head described above.

According to an important feature of my invention, a member such as a lever 78 is pivoted 110

in the handle so that it can be gripped by the hand with which the tool is carried and is arranged with a part 80 adapted to open the valve 72 against the resistance of its spring 74 and has its lower end in engagement with the leaf spring 62 so that it operates the electric switch 54. The operating lever 78 is shown as being fulcrumed on a pivot 82 carried by the lower end of the plug 66.

10 By the above-described arrangement it will be seen that the tool can be carried in one hand and the same hand can be used to manipulate the lever 78 or its equivalent to open the valve 72 to provide a blast of air through the tool and 15 at the same time to close the circuit through the resistance element 26 to heat the air. It is also important to note that when the operator lays the tool down, he cannot fail to close the air valve or to turn off the electric current. As 20 mentioned above, it is to be noted especially that all of the exterior parts of the tool are cooled by the current of air before it reaches the resistance element 26. This not only makes the tool easier to use, but also conserves the heat 25 and makes sure that it is all utilized in heating the air blast.

While one illustrative embodiment has been described in detail, it is not our intention to limit the scope of the invention to that particular embodiment or otherwise than by the terms of the 30 appended claims.

We claim:

1. A blower comprising a double-walled cup-shaped member, an end member secured to the 35 rims of said double walled cup-shaped member for closing off the space between the walls, heating means within its inner wall and an opening in the bottom of the inner wall and means for directing air into the space between the walls 40 and thence through said opening across the heating means.

2. A blower comprising a double-walled cup-shaped member, an end plate closing off the 45 space between the walls, heating means within its inner wall and an opening in the bottom of the inner wall and means for directing air into the space between the walls and thence through said opening across the heating means, and a deflector within the heating means directing 50 the current of air from said opening outwardly over the heating means.

3. A blower comprising a double-walled cup-shaped member, heating means within its inner 55 wall and an opening in the bottom of its inner wall and means for directing air from the rear into the space between the walls and thence through said opening across the heating means, a deflector within the heating means directing the current of air from said opening outwardly 60 over the heating means, said deflector being formed as a cap covering the cup-shaped double-walled member.

4. A blower comprising a casing, a cup concentric therewith and spaced therefrom, a closure for the cup and a deflector supported by the closure concentrically with respect to the cup.

5. A blower comprising a casing, a cup concentric therewith, a closure for the cup, a deflector supported by the closure concentrically with respect to the cup and a heating element supported by the cup in spaced relation to the 80 deflector.

6. A blower comprising a casing, a cup supported thereby concentrically with respect thereto, a closure for the cup, a deflector supported by the closure, a heating coil supported by the 85 cup between the cup and the deflector.

7. A blower comprising a casing having an opening therein for the admission of air under pressure, a cup supported concentrically with respect to the casing and providing in conjunction therewith an annular chamber opening into the cup, a coil supported within the cup, a closure for the cup having spaced openings and a deflector supported by the closure 90 concentrically with respect to the coil.

8. A blower comprising a hollow handle, a plug positioned therein having a conduit, a valve in the handle for controlling the conduit, a switch in the handle and an operating lever pivoted on the plug for controlling the valve 100 and actuating the switch simultaneously.

9. A blower comprising a casing having one end closed, a cup having a flange fitted snugly in the other end of the casing and an opening communicating with a chamber between the 105 outer wall of the cup and the inner wall of the casing, a coil supported by the cup concentrically with respect thereto, a closure for the cup having a part arranged concentrically with respect to the coil and openings communicating with the cup, a hollow handle secured to the closed end of the casing, a plug in the handle having a conduit communicating with the casing, a valve in the plug for controlling the conduit, a switch in the handle, leads from 110 the switch to the coil and means pivoted on the plug for controlling the valve and actuating the switch simultaneously.

10. A hot air gun comprising a cup shaped outer casing, an inner cupped shaped casing 115 containing a heater element, said inner cup having an outwardly turned flange upon the rim thereof adapted to be secured to the rim of the outer casing and an electrical connection for the heater element passing through and 120 secured to the base of said inner cup and adapted to extend through the base of the outer casing.

11. A hot air gun comprising a labyrinth heater, and a handle secured to the rear of 130 said heater, an air conduit passing longitudinally through said handle, a poppet valve having its axis longitudinally disposed in said handle, a switch, and a lever grip on one side of said handle adapted to open said valve and 135 close said switch upon depression of the lever during gripping of the handle.
